UNITED STATES PATENT OFFICE.

ISAAC SNOW, OF LAWRENCE, MASSACHUSETTS.

DIAGONAL FRICTION PIN SHUTTLE.

Application filed April 13, 1928. Serial No. 269,700.

This invention relates to shuttles and particularly to those of the self-threading type used in automatic looms although it can be used in connection with a hand threading shuttle.

In most shuttles there is a threading chamber in which is a shuttle block which has at the forward end a horn which directs the yarn down and back onto a vertical or substantially vertical pin around which the yarn passes out the eye in the side of the shuttle, and in addition it is usually necessary to provide some friction device to keep the thread on the bobbin from running out too fast.

The purpose of this device is to provide a pin which shall not only serve the purpose of directing the thread as it runs out lengthwise of the shuttle at right angles, or substantially right angles through the eye in the side, but shall also serve as an effective friction device.

This is accomplished substantially by substituting for the usual vertical pin, a pin which is preferably of larger size than is customary, which extends from the side of the shuttle opposite the eye horizontally and diagonally forward towards and ahead of the shuttle eye whereby the thread is forced instead of making a turn of 90° to make a compound or spiral turn of substantially a greater arc whereby it engages with a much larger surface of the pin than is usually the case.

I may extend this pin horizontally forward at any suitable angle and I may slant it up or down although I prefer to have it horizontal. In any case it takes the place of the usual vertical front guide pin and also serves the purpose of a friction device.

I may also, in place of the pin, form the metal itself to present a diagonal horizontal forward edge which serves the same purpose.

In the drawings, Fig. 1 is a plan view of a shuttle equipped with my device.

Fig. 2 is an elevation from the side of the shuttle eye, part of the wood being broken away to show the shuttle block.

Fig. 3 is a front elevation, Fig. 4 a side elevation, Fig. 5 a back elevation of a shuttle block removed from the shuttle. Fig. 6 is a bottom view.

Fig. 7 is a view similar to Fig. 4 of a modified type of shuttle block.

Fig. 8 is a view similar to Fig. 7 showing a slight modification.

Fig. 9 is a view from the back showing my pin applied to a shuttle block, of somewhat different character.

Fig. 10 is a view similar to Fig. 4 showing an integral metal construction in place of a removable pin.

In the drawings, A represents a shuttle 65 the body of which is made of wood, having the usual bobbin recess 10 for a bobbin B on which the yarn C is wound. 11 is a threading chamber cut in the wood in extension of bobbin recess 10 and 12 is a shuttle block recess cut out of the wood and forming part of or positioned in threading chamber 11.

18 and 19 are vertical cuts forming part 75 of the block recess for the projections 44 and 47 from block F. The shuttle eye in the wood is represented by 13 and this connects through a slot 14 with the forward part of threading chamber 11.

The shuttle block F, which is generally 80 made of metal, is positioned in the shuttle block recess 12 and is generally held in place as by a screw S in the usual manner. It is provided with a longitudinal block 85 threading chamber 31 in extension of the shuttle threading chamber 11 and its top is formed as a thread directing guide plate 32 which curves or slopes down and over at 33 from the top 133 into the block threading chamber. As shown, this guide plate has 90 a blunt thread guiding finger or nose 34 at the front and a thread guiding finger 35 at the back, there being a cut away space 135 in front of the finger 35 between it and an intermediate thread retaining guide hook G which 95 is formed in extension of the guide plate 32. This hook, where it starts at the cut away part 135 extends away at 40 from the shuttle eye and backwards and thence forward at 41 in the opposite direction towards the 100 shuttle eye and towards the thread outlet 39 which is cut away from the web 129 extending back from horn 36, which extends down from the front guiding finger 34. This reverse or end section 41 of hook G also 105 extends forward at 42.

The cut away part or the base 40 of hook G will catch any yarn which is ballooned or thrown forward from the bobbin and when the yarn has slipped over 33 and thence underneath and inside of 41 and 42 as it normally unwinds in a direction the curva-

ture of which is substantially the same as the curve at 41 and of hook G, it is very unlikely to unthread. Besides this, if the thread or yarn C should slip around finger 5 34 it will be caught in the forward extension 42 of guide hook G.

The tip end 37 of horn 36 preferably extends down below thread outlet 39 whereby the thread is directed into the thread outlet 10 and it is made difficult for it to come out.

The principal feature of my device however is the guide pin H which is preferably much larger than the usual vertical metal guide pin and preferably is of glass or porcelain or some material which resists wear.

This guide pin is shown as being passed through a hole 45 in projection 44 of the shuttle block, thence horizontally from that side which is opposite the shuttle eye and 20 the thread outlet 39 diagonally forward into a pin hole 46, either in the body of the horn 36 or between it and the web 129 across the thread outlet 39. The upper edge of this pin is preferably above the lower end 42 25 of the guide hook and considerably above the lower end 37 of the horn 36. It is positioned between guide hook G and horn 36.

As shown in Fig. 7, I may however dispense with the back guiding finger 35 and 30 the guide hook G and may use in place of the guiding finger 34 a nose such as 64 in connection with a block K which is otherwise similar to F. It has a threading chamber 61 sloping over and down into which is 35 a guide plate 62 and extending down from nose 64 is a horn 66 which terminates at 67 and behind which is a thread outlet 69. There is also a pin hole 65 through which pin H passes into another hole 63 in the 40 body of the horn 66.

As shown in Fig. 8, I may locate the pin hole 73 somewhat above or below pin hole 75 whereby pin H will not only slope diagonally and horizontally forward but also up 45 or down as desired.

As shown in Fig. 9 I may use a shuttle block M in which there is no thread directing guide plate at the top 70 but there is a longitudinal threading chamber 71 across 50 in front of which extending horizontally and diagonally is located the friction guide pin H.

As shown in Fig. 10, I may use a shuttle block P having a threading chamber 84, 55 thread directing guide plate 80, front nose or finger 81, horn 82 and guide hook 83, but, instead of a removable guide pin, having the integral friction guiding means of a generally cylindrical form as indicated between 85 and 86.

I claim:

1. The combination in a shuttle having a bobbin recess, a threading chamber in extension thereof, a shuttle block recess positioned in said threading chamber, a shuttle

eye in the side and a slot connecting said eye with the forward part of the threading chamber; of a shuttle block positioned in the shuttle block recess and formed with a longitudinal block threading chamber in extension of the shuttle threading chamber and a thread directing guide plate which slopes down and over from the top into the block threading chamber, said guide plate having a thread guiding finger at the front 70 and a thread guiding finger at the back and between them an intermediate thread retaining guide hook, said guide hook being in extension of the guide plate away from the shuttle eye thence in the opposite direction 75 towards the shuttle eye and forward, said shuttle block having at the front extending down from the front guiding finger a horn which extends down below the end of said guide hook; and a friction guide pin which 80 extends horizontally from the side opposite the shuttle eye diagonally forward across and above the bottom of the threading chamber in front of the guide hook between it and the front end of the horn, its upper 85 edge being above the lower end of the guide hook.

2. A shuttle block having a longitudinal threading chamber, a thread outlet on one side and a thread directing guide plate 95 which slopes down at the top from the side of the thread outlet into such threading chamber, said guide plate having a thread retaining guide hook in extension thereof which turns under and forward towards the side of the thread outlet, said shuttle block also having at the front end a horn which extends down below the end of said guide hook; and a friction guide pin which extends from the side of the threading chamber opposite said thread outlet diagonally and horizontally forward between the hook and the horn and across said thread outlet. 100

3. A shuttle block having a longitudinal threading chamber, a thread outlet on one side and a thread directing guide plate which slopes down at the top from the side of the eye outlet into such threading chamber; and at the front end a horn; and a friction guide pin which extends from the side 110 of the threading chamber opposite said thread outlet diagonally and horizontally forward. 115

4. A shuttle block having a longitudinal threading chamber, a thread outlet on one side, and at the front end a horn; and a friction guide pin which extends from the side of the threading chamber opposite said thread outlet diagonally and horizontally forward. 120

5. A shuttle block having a longitudinal threading chamber, a thread outlet on one side, and at the front end a horn; and a friction guide member which extends from the side of the threading chamber opposite 125

said thread outlet diagonally and horizontally forward.

6. A shuttle block having a longitudinal threading chamber, a thread outlet on one side and a thread directing guide plate which slopes down at the top from the side of the thread outlet into such threading chamber, said guide plate having a thread retaining guide hook in extension thereof which turns under and forward towards the side of the thread outlet, said shuttle block also having at the front end a horn which extends down; and a friction guide pin which extends from the side of the threading chamber opposite said thread outlet diagonally forward between the hook and the horn and across said thread outlet.

7. The combination in a shuttle having a bobbin recess, a threading chamber in extension thereof, a shuttle block recess positioned in said threading chamber, a shuttle eye in the side and a slot connecting said eye with the forward part of the threading chamber; of a shuttle block positioned in the shuttle block recess and formed with a longitudinal block threading chamber in extension of the shuttle threading chamber, a thread outlet which registers with the shuttle eye, and a thread directing top guide plate which slopes down and over from the top into the block threading chamber, said guide plate having between the front and back of the shuttle block, an intermediate thread retaining guide hook, said guide hook being in extension of the top guide plate away from the shuttle eye and having the back edge of its base raking backward and thence in the opposite direction towards the shuttle eye and tapering forward, said shuttle block having at the front a guiding finger and a horn which extends down therefrom; and guiding means positioned in front of and above the tip end of the guide hook.

8. A shuttle block having a longitudinal

threading chamber, a thread outlet on one side and at the top a thread directing guide plate which slopes down and over away from the thread outlet into the threading chamber, said guide plate having between the front and back of the shuttle block an intermediate thread retaining guide hook, said guide hook being in extension of the top guide plate away from the shuttle eye and having the back edge of its base raking backward and thence extending in the opposite direction towards the thread outlet and tapering forward, said shuttle block having at the front a guiding finger and a horn, and a guiding member positioned in front of and above the tip end of the guide hook.

9. A shuttle block having a longitudinal threading chamber, a thread outlet on one side and at the top a thread directing guide plate which slopes down and over away from the thread outlet into the threading chamber, said guide plate having between the front and back of the shuttle block an intermediate thread retaining guide hook, said guide hook being in extension of the top guide plate away from the shuttle eye and having the back edge of its base raking backward and thence extending in the opposite direction towards the thread outlet and tapering forward.

10. A shuttle block having a longitudinal threading chamber, a thread outlet on one side and at the top a thread directing guide plate which slopes down and over away from the thread outlet into the threading chamber, said guide plate having between the front and back of the shuttle block an intermediate thread retaining guide hook, said guide hook being in extension of the top guide plate away from the shuttle eye, thence extending in the opposite direction towards the thread outlet and forward.
